PORTABLE LIGHT

Stefan Novoveszky, St. Louis, Mo.

Application January 24, 1936, Serial No. 60,558

2 Claims. (Cl. 240—8.18)

The present invention relates to portable lights and, in particular, to lights with magnetic attachment devices whereby they may be mounted on any magnetic permeable surfaces.

It is an object of the invention to provide such a light that is compact and durable in construction; that will spread the light well; that may easily be disassembled for repairs; and that is inexpensive to manufacture.

10 In the drawing:

Fig. 1 is a plan view of the light.

Fig. 2 is an elevation thereof.

Fig. 3 is a plan view of the lamp with the reflector and guard removed, and the casing partly cut away.

Fig. 4 is a section on the line 4—4 of Fig. 3.

Fig. 5 is a section on the line 5—5 of Fig. 3, and

Fig. 6 is a view of the inverted reflector.

20 The light consists of a casing 10 that is tubular in shape with an upper threaded flange 11 thereon. Within this casing is fitted a spool 12 consisting of a magnetically permeable core 13 and two insulating end members 14 and 15, respectively. The core 13 is reduced in size at its ends and tightly fitted into the respective end members. This spool is fitted into the casing 10 with the end members 14 and 15 engaging tightly therein. If desired, the lower end of the casing may be peened over to prevent removal of the spool therefrom.

25 Superposed over the upper end member is an insulating disc 16 upon which is mounted a lamp socket 17. Screw elements 18 and 19 are threaded into the spool end member 15. Nuts 20 and 21 respectively engage the screw elements to hold the insulating disc 16 and the socket member 17 onto the spool. As seen particularly in Fig. 3, the socket member 17 has a flat base portion that extends to the screws 18 and 19. The entire socket member is of electrically conducting material. It is provided in the usual manner with bayonet slots 22 for the reception of a bulb 23.

30 A terminal post 24, in the form of a resilient blade, is screwed to the insulating disc 16 out of contact with the socket member 17. It is held to the disc by a screw element 25 having a nut 26 thereon and a washer 27 for holding an electrical terminal as will be described. The blade 24 extends into the socket element through an opening 28 provided therein. A reflector 29, shown in Fig. 6, is inverted and slips over the socket member. A ring 31, having threads to engage with those on the flange 11, fits over the

flange 30 on the reflector 29 and holds the same in position. A guard member 32 is formed integral with the attaching ring 31.

35 The casing 10 has an opening 33 therein through which extend two wires 38 and 39 connected to the opposite ends of a source of electrical supply. A coil 34 is wrapped about the core 13 of the spool 12 with a suitable number of turns. One lead 35 of this coil goes to the terminal 36 previously referred to as being attached to the screw element 25. The other lead 37 of the coil 34 is secured in electrical contact to the socket member 17. The wire 38 is connected to the screw member 25 and the wire 39 is connected to the screw member 18, the latter 15 of course being attached to the socket member 17.

The operation of the device is as follows:

40 The bulb 23 is inserted in the bayonet slot 22. It has the conventional contacts, one at the bottom which will engage the spring plate 24 and the other engaging the socket member 17. The current from the power source through wires 38 and 39 is directly connected to these two elements 24 and 17 by screws 25 and 18 respectively. 20 The coil 34 is connected in parallel with the bulb, since the coil lead 35 is connected to the screw element 25 and the coil lead 37 is joined to the socket member 17. Consequently, 25 as soon as the lamp is connected to a power source, the bulb will burn and the coil will be energized. As is seen the end of the core 13 extends through the end member 14. As the core is magnetically energized by the action of the coil 34, the core 13 will tend to adhere to any 30 magnetically permeable object against which it is placed.

45 When it is desired to repair the light, the ring 31 is unscrewed, the bulb is then taken out and the reflector 29 lifted away. This exposes the working parts of the connections of the device. If there is any trouble with the coil, the spool 40 may be forced out of the casing 10 and suitable repairs made, after which it may be replaced.

The reflector 29 is of such a shape that light 45 is spread in substantially all directions from the bulb. This is an advantage since the device is especially adapted to use as a trouble light in automobile repair and the like.

50 It will be observed that the structure is sturdy and compact, as well as simple in construction.

The invention having been described, it is claimed as follows:

55 1. A light comprising a hollow casing open at both ends, a spool therein including a magneti-

cally permeable core and end members, said members being of insulating material and having centrally disposed holes and said core having reduced portions extending into said holes to effect assembly of the spool, one end member serving as a closure for one end of the casing, an insulating member connected to said other spool end member in superposed relation, a bulb socket directly supported by the insulating member, a contact blade connected to said insulating member by a terminal and extended into said socket through an opening therein in non-engaging relation, said terminal, a coil between said end members and surrounding said core having one end connected to the socket and the other end to said terminal, a reflector disposed about said socket and maintained in removable relation thereto by a ring screw threadedly engaging said casing whereby said light elements may be readily completely dismantled for repair, and power leads, one connected to said terminal and one to said socket, whereby current passed through a light bulb in the socket contacting the blade passes through the coil to energize the core so that it will adhere to permeable objects to support the light.

2. A light comprising a hollow casing open at both ends, a spool therein including a mag-

netically permeable core and end members, said members being of insulating material and having centrally disposed holes and said core having reduced portions extending into said holes to effect assembly of the spool, one end member serving as a closure for one end of the casing, an insulating member connected to said other spool end member in superposed relation, a bulb socket supported by the insulating member, a contact blade connected to said insulating members and surrounding said core having one end through an opening therein in non-engaging relation, said terminal, a coil between said end member and surrounding said core having one end connected to the socket and the other end to said terminal, power leads, one connected to said terminal and one to said socket, external threads around the casing adjacent said other end member, a convex reflector around the socket and having a flange resting against the casing adjacent the termination of the threads, a flanged internally threaded ring, said ring engaging said first threads to draw its flange into clamping engagement with the flange of the reflector, and a guard fixed to said ring adapted to protect a bulb in said socket.
